The ornamental design for a vending machine island, as shown and described.

DESCRIPTION

FIG. 1 is a front elevation of the vending machine island, the rear being a mirror image thereof;

FIG. 2 is a top plan view;

FIG. 3 is a side elevation, the other side being a mirror image thereof;

FIG. 4 is a bottom plan view;

FIG. 5 is a front elevation view of a second embodiment of the vending machine as disclosed in FIG. 1;

FIG. 6 is a top plan view of FIG. 5;

FIG. 7 is a side elevation of FIG. 5, the other side being a mirror image thereof; and,

FIG. 8 is a bottom plan view of FIG. 5.

The broken away section on FIGS. 5-8 is due to the indeterminate length of the vending machine.
